Walter G. Conger,
INVENTOR.

BY *Augha B. Gair*
ATTORNEY

UNITED STATES PATENT OFFICE.

WALTER G. CONGER, OF INDEPENDENCE, MISSOURI.

ATTACHMENT FOR RADIO RECEIVING APPARATUS.

Application filed August 3, 1923. Serial No. 655,481.

To all whom it may concern:

Be it known that I, WALTER G. CONGER, a citizen of the United States, residing at Independence, county of Jackson, State of Missouri, have invented certain new and useful Improvements in Attachments for Radio Receiving Apparatus, of which the following is a specification.

This invention relates to apparatus for use in connection with radio receiving sets, having to do particularly with means whereby head telephones may be easily applied to or removed from the receiving set.

An object of the invention is to provide means of a simplified nature whereby any number of head phone outfits may be easily and quickly switched in or out of the circuit of the receiving set.

A further object is to provide an attachment of the character and for the purpose stated by the use of which one or more head phones may be used in connection with the receiving set, and which may be easily applied to or removed from the receiving apparatus.

A still further object is to provide an attachment of the character stated which is characterized by simple construction, which may be manufactured or produced at low cost, which comprises a minimum of simple and readily assembled parts, which parts are so constructed and arranged as to obviate the possibility of wear, breakage or derangement, and which will prove highly practical and efficient in operation.

With these and other objects in view, the invention consists of the features of construction, combination and arrangement of parts, hereinafter fully described and claimed, reference being had to the accompanying drawing, in which:—

Figure 1 is a plan view of an attachment constructed in accordance with the invention and illustrating in diagram the wiring circuits thereof,

Figure 2 is a bottom plan view of the attachment,

Figure 3 is a longitudinal sectional view taken upon line 3—3 of Figure 1, and

Figure 4 is a similar view taken upon line 4—4 of Figure 1.

Referring now more particularly to the drawing, 5 indicates a base, bed, block or platform of any suitable size and preferably constructed of insulated material, and to which the apparatus to be hereinafter detailed

is applied. This platform or block is preferably rectangular in form and is of a size to enable it to be conveniently used in connection with familiar types of radio receiving sets, the said block being provided as at 6 with openings through which screws may be inserted, if desired, to secure the block upon a table or other support adjacent to the radio receiving set.

Near one longitudinal edge of the block 5 are arranged spaced connectors 7 in the form of binding posts, and which I have termed the "lead-in" posts. These posts are adapted to receive the terminals of conductors 8 and 9 leading from the radio receiving set and to which, ordinarily, head telephones are attached or which connect with other sound reproducing apparatus. The posts 7 are suitably secured to the block 5 and pass entirely through the same, so that wires or conductors may be applied to the under ends thereof, as will be hereafter detailed.

Arranged in series adjacent to the opposite edge of the platform 5 are a plurality of terminals or binding posts; the latter being indicated by the reference characters 10, 11, 12, 13, 14, 15 and 16, the said posts extending entirely through the platform 5 in the same manner as the posts 7 above-mentioned. One 85 of the posts 7 is connected with an end post 10 of the above-mentioned series by means of a conductor or wire 17, arranged beneath the block 5, while each of the posts 11, 12, 13, 14, 15 and 16 constitutes one terminal 90 of a plurality of conductors indicated at 11', 12', 13', 14', 15' and 16'; these conductors having their opposite ends passed up through suitable openings in the block 5 longitudinally aligned with the center thereof 95 and constituting spaced contacts as shown.

The contact ends of the conductors 11' to 16' inclusive are disposed beneath a conductor bar 18, preferably rectangular in cross-section, and which is supported above 100 the upper surface of the bar 5 by brackets 19 as shown. A screw 20 of one of these brackets passes entirely through the platform 5 and to which one end of a conductor 21 is attached; the opposite end of this conductor being connected with the other of the lead-in posts 7.

Slidably mounted upon the conductor bar 18 is a sliding member 22, having a finger grip 23 rising from the upper side thereof, 110 and which is provided on its underside with a downwardly extending spring contact fin-

ger 24, adapted as the slide member moves along the conductor bar to engage successively the several contacts constituting the inner ends of the conductors 11' to 16' inclusive. As the said contact members are spaced apart a substantial distance, it is apparent that when the finger 24 rests upon the base in between any pair of such contacts, no circuit will be established through the slide member and conductor bar 18.

In operation, the wires 8-9 of the radio receiving set are connected with the contact member of binding posts 7 upon the platform, and the terminals 25 and 26 of a head telephone apparatus represented generally at 27 are attached to binding posts 10 and 11. The slide member 22 is then moved so that the finger 24 thereof will be in engagement with the contact member at the inner end of conductor member 11'. When so coupled, the circuit is through wire 8, binding post 7, conductor 17, binding post 10, terminal 25 of head phone, head telephone 27, terminal 26 of head phone, binding post 11, conductor 11', contact finger 24, conductor bar 18, securing screw 20, conductor 21, binding post 7 and wire 9 leading to the radio receiving apparatus. The circuit is thus established through the head telephones 27 and one person may listen in. If it is desired to attach an additional set of head telephones to the circuit, one terminal thereof will be attached to binding post 11 and the other terminal to binding post 12, and the movable contact member 22 will be moved so that the finger thereof will be engaged with the contact constituting the inner end of the conductor 12'. The circuit will then be in through wire 8, conductor 17, binding post 10, terminal 25 of the head telephones, head phone 27, terminal 26 of the head telephones, post 11, then through the terminals of the additional set of head telephones, as well as the head phone per se, and back through conductor member 12', as will be understood. Any number of additional head phones, up to six, may be plugged in to the circuit, it merely being necessary to attach the terminals thereof to a pair of successive binding posts of the series, and moving the sliding contact member 22 so that the finger thereof will engage the proper contact.

From the foregoing it is apparent that I have provided means of an extremely simple nature, and of easy operation, which may be effectively used in coupling any number (up to six) head phones to the circuit of the radio receiving apparatus. While, in the present instance, means are provided for coupling as many as six head phones to the circuit, it is to be understood that binding posts for the accommodation or attachment of more or less numbers of head phones may be used. In the present instance, for pur-

poses of illustration and convenience of description only, the several members to which the conductors are attached are termed "binding posts," however it will be understood that any preferred type of terminal connector may be equally as well used, and it is also to be understood that the present device is not to be limited to the use with any particular type of binding post or terminal connector.

Furthermore, it is apparent that changes in the various details of construction, the size, proportion and arrangement of parts, may be liberally resorted to if desired without departing from the invention as defined by the claims.

Having thus fully described my invention, I claim:

1. In an attachment of the class described, a base, binding posts on the base to receive the lead-in wires from radio receiving apparatus, a series of posts on said base arranged in spaced relation and adapted to receive the terminals of sound reproducing apparatus, a connection between one of the said lead-in posts and an end post of said series, contact members connected with each of the remaining posts of said series, a conductor bar, a contact member slidable upon said bar and adapted to engage successively with said contacts as it is moved along the bar, and a connection between said bar and the other of said lead-in posts.

2. In an attachment of the class described, a base, a pair of lead-in posts on said base, a series of posts arranged in spaced relation upon said base, a connection between one of said lead-in posts and the end post of said series, a plurality of spaced contacts on said base corresponding in number to the remainder of said posts of the series, a conductor connecting each contact member with its respective post, a conductor bar overlying the said contacts, a slide member arranged upon said bar, a contact finger on said slide member adapted successively to engage with said contacts, and a connection between said bar and the other of said lead-in posts.

3. In an attachment of the class described, a base, a pair of lead-in posts on said base, a series of posts on said base spaced from each other and from said lead-in posts, a conductor connecting one of said series of posts with one of said lead-in posts, a plurality of spaced contacts corresponding in number to the remainder of said series of posts, a conductor for each contact connecting it with its corresponding post of the series, a conductor bar adjacent said contacts, a connection between said bar and the other of said lead-in posts, and a slide conductor on said bar adapted to be moved to successively engage said contacts.

4. In an attachment of the class described,

5 a base formed of insulating material, a pair
of lead-in posts on said base, a series of
posts on said base, a series of contacts on
said base spaced from each other and corre-
sponding in number to the series of posts,
10 a conductor connecting each contact with
its respective post of the series, and a slide
contact member on said base electrically
connected with one of said lead-in posts and
adapted to engage with said contact mem-
bers.

15 5. In an attachment of the class described,
a base formed of insulating material, a
series of contacts on said base and a series
of posts corresponding to the contacts, a
conductor connecting each contact with its
20 respective post, means on said posts for con-
necting the terminals of electric apparatus
thereto, a slide member adapted to engage
with said contacts, a connection between
25 said slide member and an extraneous source
of energy, a post insulated from said con-
tacts, and means whereby said post may be
connected to the other pole of said extrane-
ous source of energy.

6. In an attachment of the character de-
scribed, a base formed of insulating mate-
rial, a pair of lead-in posts on said base par-
allel with each other and near one edge of
the base, a series of posts arranged in par-
allel alinement near the opposite edge of the
base, a connection between one of said lead-
in posts and one end post of said series, a
plurality of spaced contacts alined with
each other and spaced equidistantly between
30 said lead-in posts and series, said contacts
being in number one less than said spaced
posts, a conductor connecting each contact
member with its respective post, a conduct-
or bar overlying said contacts, a slide mem-
ber on said bar, a contact finger on said
slide member to successively engage said
contacts, and a connection between the lower
40 end of said bar and the other of said
lead-in posts.

45 In testimony whereof I affix my signature
hereto.

WALTER G. CONGER.
